UNITED STATES PATENT OFFICE.

MARCUS EDWY WETTENHALL, OF POMONA, NEAR STAWEll, VICTORIA,
AUSTRALIA.

FRUIT-GRADING MACHINE.

No. 833,991.

Specification of Letters Patent.

Patented Oct. 23, 1906.

Application filed April 20, 1905. Renewed August 23, 1906. Serial No. 331,802.

To all whom it may concern:

Be it known that I, MARCUS EDWY WETTENHALL, a citizen of the Commonwealth of Australia, and a resident of Glen Holford, 5 Pomona, near Stawell, in the State of Victoria, Australia, have invented new and useful Fruit-Grading Machines, of which the following is a specification.

The object of my invention is to provide a 10 cheap and effective machine for grading fruit.

In order that my invention may be readily understood, I will describe it by reference to the accompanying drawings, in which—

Figure 1 is a perspective view, and Fig. 2 a 15 plan, of a fruit-grading machine constructed according to my invention, while Fig. 3 is a vertical longitudinal section on line *a* *a*, Fig. 2; and Fig. 4 is a vertical transverse section on line *b* *b*, Figs. 2 and 3. Figs. 5 and 6 20 are views of a certain detail in the construction of my invention.

The same reference-numerals indicate the same or corresponding parts in all the figures.

My invention includes two side frames 1 25 and 2, the height and length of which will vary with conditions. They are situated some distance from each other and united by cross-pieces or frames 3 and 4.

At the discharge end of the machine is a 30 drum 5, which extends between the two side frames 1 and 2. To one end of this drum 5 is attached a crank-handle, whereby or by other means—such, for instance, as the chain-and-sprocket gear shown in the drawings or by a belt-pulley—the said drum, hereinafter called the “main” driving-drum, is 35 rotated, or by suitable means the said drum may be rotated from the other end of the machine. Upon this drum 5 is a pinion 6, gearing into a corresponding pinion 7, situated upon an auxiliary driving-drum 8, which is contiguous to the said main driving-drum 5.

Extending between the side frames 1 and 2 at the feeding end of the machine is a cross- 45 roller 10, hereinafter called the “inner” roller. Also extending across the machine between the side frames is a cross-roller 11, hereinafter called the “tension-roller.” This roller is adjustable in and presses downward 50 upon belts hereinafter described in order to keep them tight. It is supported at the outer ends by links 12, pivoted to the side frames, so that it can be adjusted in a vertical plane. Other links 9 depend from the

axle of this tension-roller 11 and connect it 55 by a hook and cross-piece, as shown, or otherwise to a weighted lever 13, whose tendency is to always keep the roller 11 pressing downward upon the belt or belts, and thereby keep them tight. 60

Around the inner rollers 1, 10, and 11 on the feeding and discharge end of the machine and passing underneath the driving-roller 5 and over the auxiliary driving-roller 8 is an endless belt 14. Through this belt 14 are 65 perforations of any size required.

At the feeding and discharge end above each roller 5 and 10, before referred to, are cross-rollers 15 and 16. These are called the “lower intermediate cross-rollers.” 70

Around the lower intermediate cross-rollers and around the inner or lower band or belt 14, before described, is another band or belt 17, hereinafter called the “lower intermediate belt.” This latter, which is longer 75 than the inner band or belt 14, is provided with holes of a larger size than those in said lower belt.

At the feeding and discharge end and above each intermediate roller 15 and 16, before described, other rollers 18 and 19 are placed, around which a belt 20 passes in a similar manner to the belt 17. Above these rollers 18 and 19 are similar rollers 21 and 22. These are called the “upper” or “outer” rollers, and around them and the three bands 14, 17, and 20 before alluded to passes an endless band or belt 23, hereinafter called the “outer” or “upper” band. Through this band or belt, which is longer than those before mentioned, are perforations, which are larger than those in the preceding belts, the whole forming a series of superimposed perforated bands or belts adapted to be revolved round the rollers. Near the feeding end of 95 the machine transverse guide-boards 40 are placed, one above each band or belt. These guide-boards have openings 41, as shown in Figs. 4, 5, and 6, through which any fruit which is too large to pass through the holes in 100 the belt will be drawn by the movement of the latter.

Each opening 41 is provided with a flexible tab 42, of leather or other suitable material, which is weighted at its lower end to prevent 105 any fruit passing through the opening 41 unless it is retained in one of the holes in said band or belt.

Longitudinal partitions 43, which extend from each guide-board 40 to the feeding end of the machine, are provided to keep the fruit over each respective line of holes in the bands or belts, said partitions having battens 44 fixed to their lower edges in order to guide the fruit more effectively.

At one side of the machine a door 45 is provided to enable the operation of the machine to be watched, the said door having guiding-battens 44 fixed to it in the same manner as the partitions 43.

Near the discharge end of the machine and beneath the upper intermediate and lower bands or belts 23, 20, and 17 and 14 are placed or sloped elevating-plates 24. These are for raising gently out of the holes or perforations the fruit which goes only partly through the bands as the said fruit is drawn over the plate by the band. The fruit when raised rolls gently off into receivers or discharge-chutes at the side. The fruit on the upper band may be liberated either at the side or the end, as shown in the drawings.

Above the discharge end of each band diverting-boards 25 are placed at an angle with the said bands, so that any fruit carried by the band will contact with the diverting-board and will thereby be diverted so that it will roll into a discharge-chute at the side of the machine.

At the feeding end of the machine and above the upper band is placed a feeding-chute 26, which is hinged at 27, so that it can be adjusted by means of rack 28 to any desired slope. At the discharge end of the machine and in a line with the upper band is placed a discharge-chute 29 for the largest fruit and three superimposed chutes 30, 31, and 32, respectively, to carry off the second, third, and fourth grade fruit, while a fifth chute 33 is provided to discharge the undersized and rejected fruit. Each of these chutes, with the exception of the last, is provided with a hinged fruit-case carrier 34, designed to hold an export or other fruit case in such a position that the fruit will roll down the side of the case. Each carrier is counterweighted, so that the case is gradually lowered into an upright position as it is filled, thus saving the fruits from getting bruised as they roll in and withal allowing the case to be filled to the top. The counterweights 35 employed for this purpose are attached to the end of a curved guide 36 by a cord 37, which passes over two blocks 38 and 39, as shown in Fig. 3. These fruit-case carriers 34 are constructed in two pieces, one of which is slotted, so that it can be bolted to the other piece in any desired position, as shown in Fig. 3, so that the length of the carrier can be adjusted to hold any-sized case up close to the end of the chute.

I do not bind myself to the number of endless bands or belts, the material of which

they are made, nor to the means of adjusting the tension on the same, since these will vary with conditions.

The cycle of operations with my invention is as follows: The feeding-chute 26 is filled with fruit and the bands or belts are set in motion. The fruit is then passed on to the upper band or belt 23. Some pass onwards to the discharge-chute 28 and some fall through onto the first intermediate band 20. Some pass onwards from this band and out at chute 30 and some fall through the holes or perforations in the said belt onto the lower intermediate band or belt. Some pass through the holes in this band onto the lower band 14 and some pass through this band to the chute 33, which directs them to a receiver at the side of machine. Those which pass through are liberated from the machine by a chute or other means. My fruits are therefore divided up into grades dependent upon the size of the perforations of the bands and the number of the said bands. The first fruit which passes down any particular chute are received in a case which is practically lying on its side, so that said fruit rolls gently to the bottom of the case, and as the weight of fruit in the case increases the counterweight is drawn up and the case becomes more and more upright until it is full.

What I claim as my invention, and desire to secure by Letters Patent, is—

1. In a machine of the class described, the combination of driving mechanism; a series of grading-belts, all of which pass around a pair of main rollers and each of which pass around a separate pair of supplementary rollers; and said main and supplementary rollers.

2. In a machine of the class described, the combination of a plurality of pairs of rollers arranged one above the other; a series of grading-belts which contact for a portion of their length with one another and which for the remainder of their length are separated by said rollers; and means for moving said belts.

3. In a machine of the class described, the combination with a perforated grading-belt and means for driving the same, of a perforated cross-piece through which passes fruit too large to pass through said belt.

4. In a machine of the class described, the combination with a perforated grading-belt and means for driving the same, of a perforated cross-piece through which passes the fruit too large to pass through the belt; and means for controlling the openings in said cross-piece.

5. In combination in a machine of the class described, perforated movable grading members and means for driving the same, with a perforated stationary grading member provided with automatic closures for the holes therein.

6. In combination in a machine of the class described, a plurality of perforated grading belts; inclined stationary plates mounted below said belts and close thereto for raising the fruit from the holes in said belts; and means for driving said belts.

7. A fruit-grading machine made up of a perforated endless belt; means for driving the same; and a stationary perforated grading member extending transversely of said belt and above the same; said belt forcing through the holes in said stationary grading member the fruit too large to pass through the holes in said belt.

15 8. A fruit-grading machine made up of a

perforated endless belt; means for driving the same; and a stationary perforated grading member provided with automatic closures for the holes therein and extending transversely of said belt and above the same; said belt forcing through the holes in said stationary grading member the fruit too large to pass through the holes in said belt. 20

In testimony whereof I have signed my name to this specification in the presence of 25 two subscribing witnesses.
